CLAIM

The ornamental design for a vehicle, as shown and described.

DESCRIPTION

FIG. 1 is a front view of a vehicle showing my new design;
FIG. 2 is a left, front perspective view thereof;
FIG. 3 is a left, rear perspective view thereof;
FIG. 4 is a right side view thereof;
FIG. 5 is a left side view thereof;
FIG. 6 is a rear view thereof;
FIG. 7 is a top view thereof; and,
FIG. 8 is a bottom view thereof.

The broken lines shown throughout the drawing views are
for illustrative and environmental purposes and form no part
of the claimed design.
